UNITED STATES PATENT OFFICE.

ARTHUR L. BENEDICT, OF OCEAN GROVE, NEW JERSEY.

WINDOW AND DOOR SCREEN.

SPECIFICATION forming part of Letters Patent No. 290,312, dated December 18, 1883.

Application filed March 16, 1883. (No model.)

To all whom it may concern:

Be it known that I, ARTHUR L. BENEDICT, a citizen of the United States, and a resident of Ocean Grove, in the county of Monmouth and State of New Jersey, have invented certain new and useful Improvements in Window and Door Screens, of which the following is a specification.

My invention relates to screens adapted to be applied to windows, doors, and the like objects, so that when the object is opened the screen will be drawn over the space from which the object has receded, and thereby cover the otherwise open space and prevent insects and other matters from entering the rooms; and it consists in the construction and the combination of parts hereinafter particularly described, and then sought to be specifically defined by the claims.

20 In the drawings, Figure 1 is a side view of the device applied to a window; Fig. 2, a cross-section through the device detached from the window; and Fig. 3, a perspective in cross-section, showing the device closed.

25 In the accompanying drawings, the letter A indicates a box or case, of wood or other suitable material, provided with a detachable side or back, B, and having end plates or blocks, C, perforated for the passage of screws or other 30 fastening devices for securing the case to a window or other frame. The box incloses an ordinary spring-shade or other suitable spring-actuated roller, D, which is journaled in the ends of the box so as to turn, and has secured 35 to it one end of a gauze or other netting, E, the other end of which is secured to the inside of the back B. The back B is made separate from the box, and is held thereto by the netting and tension of the spring in the roller, 40 and is preferably provided with a bead, a, which will fit over onto the top of the box, so as to make a close joint and cover the netting from sight when the box is closed. The screen device is further provided at each end with a 45 protecting strip or band, F, made of webbing, flexible metal, or wood, or other suitable material, one end of which strip is secured to the inside of the top of the box or case, and the strip then passed up through a slot, b, in the 50 bead of the movable side, and thence to the rear of the side, preferably fitting into a recess made in the rear of the side, so that the

webbing will be flush with the surface of the side, and thence to the under side of the case, and the end then secured to the case. These 55 strips thus applied form looped or double strips, equal in length to the length of the gauze or netting when extended, and are intended to cover the open spaces at the sides of the netting, caused by the netting drawing 60 or bagging toward the center of the screen, or by other causes. These protecting or covering strips very effectually serve their purpose, and might be applied in various ways for the same purpose without departing from the 65 spirit of that feature of my invention; but the method which I have described I consider to be the best.

If desired, flanges G, rounded on their inner edges, so as not to cut the protecting strips, 70 may be secured to or formed on the edge of the case at both ends where the strip passes from the inside of the top of the case, so as to hold the strip close to the end face of the netting, and thereby more effectually prevent the 75 entrance of any matter from the outside between the strips and netting.

The screen, constructed as described, is applied to a window-frame by resting the case on the window-sill and securely holding it to its 80 place by screws passed through the end plates or blocks, C, into the sides of the window-casement. The movable side of the case is then suspended from the window-sash by means of pins H, projecting from the face side 85 of the sash-rail and entering holes made in the movable side for that purpose. Two pins, H', are driven into the side stops or parting-strips of the window at sufficient distances from the fixed portion of the case, as shown, 90 to allow the protecting-strips to be drawn tightly over them. If the window-sash be now raised, it will carry with it the movable side and extend or draw out the netting, so as to cover the space from which the window-sash 95 is moved. At the same time the netting passes between the protecting-strips, which cover the netting on its opposite faces next to the side of the window-frame, so that if the netting be drawn away from the sides the strips will 100 cover the open spaces thus formed, and prevent the entrance of any matter.

If it is desired to reach the outside of the window, it is only necessary to lift the mova-

ble side from off its suspending-pins; and when the netting is not in use the movable side is disconnected from the window-sash and folded into its case, so as to completely cover 5 the netting, thus sheltering it from dust and hiding it from view, so that nothing but an attractive-looking case is presented to view.

The case can be very readily detached from one window-frame and applied to another 10 without cutting the frame for its application. It may also be applied to either the top or bottom of the frame, so as to work vertically, or applied to a sliding window or doorway, so as to work horizontally, and will work from one 15 side of a frame as well as from another.

While in store for sale or stored away for keeping, the case forms a complete covering for the netting, protecting it from dust and decay.

I do not claim, broadly, a spring-actuated 20 roller carrying a flexible screen, combined with a window frame and sash and a case inclosing the screen when rolled up, as this is old.

Having fully described my invention and set forth its merits, what I claim is—

25 1. The combination of the removable box comprising two parts adapted to be separated from each other, and when brought together to form a closed case inclosing a screen, a spring-actuated roller journaled in one section of the box, and a screen connected at one end to the other section of the box and at the opposite end to the spring-actuated roller, substantially as and for the purpose set forth.

30 2. The combination of the removable box comprising two parts adapted to be separated from each other, and when brought together

to inclose a screen, a spring-actuated roller journaled in one section of the box, a screen connected at one end to the other section of the box and at the opposite end to the spring-actuated roller, and the protecting-strips connected at both ends to one section of the box and passed through guide-slots in the other section, substantially as and for the purposes set forth. 40

3. The combination of the movable box comprising two parts adapted to be separated from each other, and when brought together to inclose a screen, a spring-actuated roller journaled in one section of the box, a screen connected at one end to the other section of the box and at the opposite end to the spring-actuated roller, and the protecting-strips connected at both ends to one section of the box and passed through guide-slots in the other section, substantially as and for the purposes set forth. 50

4. The combination, with a screen connected at one end to a spring-roller and at the other end to a movable frame, of protecting-strips 60 extended along the sides of the screen, and adapted to close spaces formed by the screen drawing from its sides toward its center, substantially as described, and for the purposes set forth.

In testimony whereof I have signed my name to this specification in the presence of two subscribing witnesses.

A. L. BENEDICT.
